"Office Action of U.S. Counterpart Application", issued on Apr. 17, 2013, p. 1-p. 6.

Primary Examiner — Melanie H Tung*(74) Attorney, Agent, or Firm* — Jianq Chyun IP Office(57) **CLAIM**

The ornamental design for a display screen with a graphical user interface, as shown and described.

DESCRIPTION

FIGURE is a front view of a display screen with a graphical user interface showing our new design.

The broken line showing of the display screen is for the purpose of illustrating environmental structure and forms no part of the claimed design. The broken line showing the remainder of the graphical user interface forms no part of the claimed design.
